CLAIM

The ornamental design for a fishing lure with slot and blade as shown and described.

DESCRIPTION

FIG. 1 is a perspective view of a fishing lure with a slot and blade that shows the new design.

FIG. 2 is a left side view of the fishing lure shown in FIG. 1. (The right side view of the fishing lure is a mirror image and not shown.)

FIG. 3 is a top view of the fishing lure shown in FIG. 1. FIG. 4 is a front view of the fishing lure shown in FIG. 1; and,

FIG. 5 is a detail perspective view of the slot and blade of the fishing lure shown in FIG. 1.

The broken lines in the Figures do not form a part of the claimed design.

1 Claim, 3 Drawing Sheets
